BUTTON ATTACHING MEANS

Henry Anthony Smitt, Fort Lewis, Wash.

Application January 11, 1940, Serial No. 313,437

4 Claims. (Cl. 24—103)

My invention relates to means for attaching buttons to garments without sewing, and it particularly has for its object to provide a simple and effective device that can be manufactured at a nominal cost and will readily and conveniently serve its intended purposes.

Other objects will in part be obvious and in part be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawing, in which:

Fig. 1 is a side elevation of a button secured to a piece of cloth by the improved attaching means, the cloth being shown in section.

Fig. 2 is a rear elevation of the button and the attaching means.

Fig. 3 is a detail perspective view of the double pointed pin.

Fig. 4 is a detail perspective view of the pin-holder and guard member.

In the drawing, in which like numbers of reference indicate like parts in all the figures, 1 is the cloth to which the button 2 is to be fastened, the button 2 having the usual eye-loop 3.

My invention comprises two units, one the button-holding pin unit (Fig. 3) and the other the pin-securing and guard unit (Fig. 4).

The pin unit comprises a piece of stiff springy wire bent upon itself to form a U-shaped portion or open loop 4, and two legs each composed

of the portions 5 which lie in a plane at about an angle of 95° or so to the loop 4, the portion 6, 6 bent slightly inwardly (i. e., toward the loop side), and the pointed extremities 7, 7 which lie in a plane about parallel to and offset from that containing the portions 5, 5.

The pin-securing and guard unit is composed of wire formed into a flat, approximately closed eye 8, two slightly diverging legs 9, 9, and lateral open loops formed by the portions 10, 11, 12, and

13. The ends of the wire are formed into pointed extremities 13. The parts 9, 10, 11 and 12 lie in one plane, while the eye 8 and the pointed extremities 13, 13 are bent over at angles to said

one plane (see Fig. 1).

In using my invention the pin unit (parts 4 to 7 inclusive) has one leg passed through the eye-loop 3 and then both points 7 are passed through the cloth 1 and through the eye 8. The legs 5, 6, 7 are spread apart and slipped sidewise

over the loops 10—11—12 whereupon they will spring toward each other again until arrested by the pointed extremities 13.

The pointed extremities 13 can then be pressed into the fabric 1 which protects the user from scratches, and also tends to prevent swiveling of the button.

While I have shown the preferred embodiment of my invention, I wish it understood that slight changes in it may be made without departing from the spirit of the invention and the appended claims.

What I claim is:

1. In a button attaching means, a pin unit comprising a wire bent upon itself to form a loop and two legs, the legs lying in a plane at an angle to that of the loop, and a pin-securing and guard unit comprising a wire bent to form an eye and two limbs the latter including laterally projecting loop portions, the ends of the wire being bent out of the plane containing the remainder of the limbs, said pin unit's loop being designed to be passed through the eye of said pin-securing and guard unit and said legs being designed to underlie said loop portions when the units are assembled in use.

2. In a button attaching means, a pin unit comprising a wire bent upon itself to form a loop and two legs, the legs lying in a plane at an angle to that of the loop, and a pin-securing and guard unit comprising a wire bent to form an eye and two limbs the latter including laterally projecting loop portions, the ends of the wire being bent out of the plane containing the remainder of the limbs, said ends of the wire pin-securing and guard unit being pointed, said pin unit's loop being designed to be passed through the eye of said pin-securing and guard unit and said legs being designed to underlie said loop portions when the units are assembled in use.

3. In a button attaching means, a pin unit comprising a wire bent upon itself to form a loop and two legs, the legs lying in a plane at an angle to that of the loop, and a pin-securing and guard unit comprising a wire bent to form an eye and two limbs the latter including laterally projecting loop portions, the ends of the wire being bent out of the plane containing the remainder of the limbs, said eye lying in a plane at an angle to that containing the limbs, said pin unit's loop being designed to be passed through the eye of said pin-securing and guard unit and said legs being designed to underlie said loop portions when the units are assembled in use.

4. In a button attaching means, a pin unit

comprising a wire bent upon itself to form a loop and two legs, the legs lying in a plane at an angle to that of the loop, and a pin-securing and guard unit comprising a wire bent to form an eye and two limbs the latter including laterally projecting loop portions, the ends of the wire being bent out of the plane containing the remainder of the limbs, said eye lying in a plane

at an angle to that containing the limbs, the ends of the wire of the pin-securing and guard unit being pointed, said pin unit's loop being designed to be passed through the eye of said pin-securing and guard unit and said legs being designed to underlie said loop portions when the units are assembled in use. 5

HENRY ANTHONY SMITT.
